UNITED STATES PATENT OFFICE.

JOHN H. RYMER, OF ETOWAH, TENNESSEE.

TRANSPOSING-KEYBOARD.

1,146,104.

Specification of Letters Patent.

Patented July 13, 1915.

Application filed October 25, 1913. Serial No. 797,275.

To all whom it may concern:

Be it known that T. JOHN H. RYMER, a citizen of the United States, residing at Etowah, in the county of McMinn and State 5 of Tennessee, have invented new and useful Improvements in Transposing-Keyboards, of which the following is a specification.

The invention relates to transposers, and more particularly to the class of transposing keyboards for pianos and organs.

The primary object of the invention is the provision of a device of this character which can be mounted within the casing of a musical instrument so that the keys thereof can be readily and easily shifted simultaneously with each other so as to vary the position of the keys to enable a piece of music written in one key to be played with accuracy in another key, the device being novel in form 20 and readily and easily operated.

Another object of the invention is the provision of a transposer of this character which is extremely simple in construction, reliable and efficient in its purpose, and inexpensive in manufacture and installation.

With these and other objects in view, the invention consists in the construction, combination and arrangement of parts as will be hereinafter fully described, illustrated in 30 the accompanying drawing, and pointed out in the claims hereunto appended.

In the drawings: Figure 1 is a fragmentary vertical transverse sectional view through a piano, showing the transposer constructed in accordance with the invention applied thereto. Fig. 2 is a fragmentary plan view of the transposer. Fig. 3 is a perspective view of the shiftable key-frame. Fig. 4 is a fragmentary front elevation of a modified form of transposer, adapted especially for use in organs. Fig. 40 5 is a fragmentary end elevation thereof. Fig. 6 is a perspective view of the transposer.

Similar reference characters indicate corresponding parts throughout the several views in the drawing.

Referring to the drawing in detail, A designates the key bed of a piano casing, which is of the ordinary well-known construction, and in which is fitted the transposer presently described.

The transposer comprises a shiftable key frame 10 which is formed medially there-of with a balance rail 11, the same being extended longitudinally throughout the length

of the said frame. On opposite sides of the rail 11 at the front and rear edges of the frame are front and rear rest rails 12 and 13 respectively, the frame 10 being slidably held within the key bed A in any suitable manner. The keys 13, are fulcrumed on the balance rail 11 in the usual manner, so that the rear end of each will extend beneath the abstract 14 of the hammer action (not shown) of the piano, which is of the ordinary well-known construction.

Suitably mounted on the casing of the piano at one end of the key bed A, or at any other suitable point, is a scale plate 15 on which is exposed a key chart of any preferred type, and with this chart cooperates a pointer 16 which projects from an upright handle 17 carried by the key frame 10 and in convenient reach of the operator of the piano, so that by the coöperating pointer 16 and the scale on the plate 15 the keys carried by the frame 10 can be synchronously shifted on manually moving the frame for the playing of a piece of music in any determined key other than that in which the same is written.

Above the keys 13 and journaled in the casing of the piano is a horizontal shaft 18 to which is fixed a frame 19 having bars 20 and 21 respectively, the bar 20 being designed to engage projections 22 formed on the abstracts 14 of the hammer action to lift the said abstracts when the key frame is to be shifted so as to avoid interference by the abstracts 14 should it remain in normal lowered position. The bar 21 is adapted to be lowered onto the keys 13 so as to prevent the rocking thereof when the abstracts 14 have been lifted. Connected to the shaft 18 is an operating crank 23 having connected thereto a pull rod 24 which extends through the front wall of the casing of the piano and carries on its outer end a knob 25 whereby it may be manually operated for the shifting of the frame 19 prior to moving the key frame in a manner as hereinbefore described.

In Figs. 4, 5 and 6 there is shown a modified form of transposer which is adapted especially for use in organs, and comprises a substantially rectangular shaped frame 26 forming the frame for the organ keys. The keys are mounted upon the frame in any suitable manner, while fixed in the inner longitudinal rail of the said frame 26 are substantially U-shaped hinged yokes 27 which are pivoted in stationary pieces 28 fixed

within the casing of the organ. The yokes 27 are of a length to permit the lateral shifting of the frame 26, as well as the swinging thereof for raising and lowering it. The 5 forward longitudinal rail of the frame 26 normally rests in bearings 29 suitably fixed in the casing of the organ at the front thereof when the keys are in position for the 10 playing of the instrument. It is of course understood that the arrangement of the keys is as usual, each overlying its respective push pin 30 of the pneumatic valve for controlling the reeds of the organ, the frame being raised and lowered in a manner 15 presently described. Swingly supported in the bearings 29 is a series of levers 31, one of which is of greater length than the remaining levers, and carries a handle 32, and said levers have formed thereon crank extensions 20 33 carrying friction rollers 34 underlying the outer longitudinal rail of the frame 26 so that on the shifting of the levers in one direction the cranks 33 will swing to raise the said frame, and on shifting of the levers 25 in the reverse direction the said frame will become lowered. These levers 31 operate in unison through the medium of a connecting rod 35 which is suitably pivoted thereto. It is of course understood that the levers are 30 disposed exteriorly of the casing of the organ so that the handle 32 is in convenient reach of an operator whereby on manipulating it the frame 26 can be raised so that the said frame can be shifted in a manner presently described. The frame at one end has 35 fixed thereto an upright handle 36 carrying a pointer 37 which is adapted to coöperate with the chart or scale of a scale plate and adapted to be suitably fixed to the casing of 40 the organ. The handle 36 when manually operated will shift the frame 26 after it has been raised in a manner hereinbefore described, so that the keys of the organ will be shifted, thereby varying the position of the 45 same relative to the organ action so that

music can be played in any key or in the same key in which the same is written. The scale enables a person to accurately determine the desired extent to shift the keys of the instrument so that the music can be 50 played in a predetermined key selected by the player of the instrument.

It is to be understood of course that changes, variations and modifications may be made within the invention such as come 55 properly within the scope of the appended claims without departing from the spirit or sacrificing any of the advantages of the said invention.

From the foregoing it is thought that the 60 construction and manner of operation of the invention will be clearly understood, and therefore a more extended explanation has been omitted.

What is claimed is:

1. A piano having a transposing keyboard, 65 said keyboard comprising a movable frame having a balance rail supporting the keys of the piano, and a manually operable lever pivotally supported above the keys and 70 having bars for simultaneously lifting the abstracts of the piano action and locking the keys against rocking movement on the balance rail.

2. A piano having a transposing keyboard, 75 said keyboard comprising a movable frame having a balance rail supporting the keys of the piano, a manually operable lever pivotally supported above the keys and having bars for simultaneously lifting the abstracts of 80 the piano action and locking the keys against rocking movement on the balance rail, a pointer carried by the handle and a scale to coöperate with the pointer.

In testimony whereof I affix my signature 85 in presence of two witnesses.

JOHN H. RYMER.
